UNITED STATES PATENT OFFICE.

MATHEW M. HYLAND, OF SEATTLE, WASHINGTON.

EDUCATIONAL CHART.

Application filed April 11, 1922. Serial No. 551,527.

To all whom it may concern:

Be it known that I, MATHEW M. HYLAND, a citizen of the United States, residing at Seattle, in the county of King and State of Washington, have invented certain new and useful Improvements in Educational Charts, of which the following is a specification.

This invention relates to educational charts especially adapted for use by children.

An important object of this invention is to provide an educational chart having simple means whereby children may learn the alphabet and learn to read simple words by 15 associating the letters of the alphabet and simple words such as "dog, cat, and rat," with various colors.

A further object of the invention is to provide a chart which will not only teach 20 the children to read simple words and the various letters of the alphabet but will also enable the child to distinguish different colors.

Also, the invention aims to provide an 25 educational device which may be manufactured either in chart or book form at a small price.

Other objects and advantages will be apparent during the course of the following 30 description.

In the accompanying drawing forming a part of this application and in which like numerals are employed to designate like parts throughout the same, the figure represents a chart constructed in accordance with 35 this invention.

In the drawing wherein for the purpose of illustration is shown a preferred embodiment of the invention, the numerals 5 and 40 6 designate parts 1 and 2 respectively of the chart and by reference to the drawing it will be seen that each chart is divided into twenty-six sections or squares, making fifty-two sections in all.

45 It might be said that parts 1 and 2 are divided into rows of sections and that the rows of part 1 are of different colors. That is to say, the upper row which is designated by the numeral 8 may be five different shades 50 of green, one shade for each square. Likewise, the sections of the row 9 may be five different shades of red, while the sections of the rows 10, 11 and 12 may be different shades of blue, yellow and purple respectively. The lowermost row of each part

consists only of one section and this may be of any desired color.

Summarized, it might be stated that part 1 consists of a plurality of rows of squares of different colors, the squares in each row 60 being of different shades of the same color, and, by reference to the drawing, it will be seen that pictures of such articles as an ax, a boy, a church, a dog, an egg, and a fan appear in the various colored squares or sections of the rows. Of course in carrying out the invention all of the twenty-six sections in part 1 will be provided with pictures, the number being limited in this illustration to simplify the description. 70

Part 2 is also provided with twenty-six squares all of which are provided with colors similar to the colors in part 1. However, the colors in part 2 are mixed up so that when a child is seeking to find a color in 75 part 2 which appeared in part 1, it will have to look over the various colors. That is to say, the green square in part 1 in which the ax appears will not be the first square in the row but will possibly be the third square in 80 part 2. Also the red square in which the fan appears will not be duplicated in the first square of row number 2 of part 2 but will possibly appear in the fifth row from the top. 85

It is thus seen that there are corresponding colors in parts 1 and 2 and in the squares of part 2, the word is printed instead of a picture of the article appearing as in part 1. 90

In use, the child will observe that the light green square in part number 1 bears the picture of an ax and will carry a mental picture of this color in his mind while looking for a corresponding color in part 95 2. Upon finding the corresponding color in part 2, the word "ax" will be written out, all of which enables the child to learn the alphabet and to learn to read simple words.

In the manufacture of a number of charts 100 part 1 of each chart will be a duplicate of all other charts while part 2 will be different in each instance.

I claim:—

1. An educational chart divided into parts 105 1 and 2, part 1 being provided with a series of rows of squares of different colors, the squares in each row being different shades of the same color, part 2 also being provided with squares colored similar to the squares 110

in part 1, part 1 being provided with pictures of objects in the squares and part 2 being provided with words indicating the object in the similarly colored square in part 1.

2. An educational chart divided into parts 1 and 2, part 1 being provided with a series of rows of squares of different colors, the squares in each row being different shades 10 of the same color, part 2 also being provided with squares colored similar to the squares in part 1, part 1 being provided with pic-

tures of objects in the squares and part 2 being provided with words indicating the object in the similarly colored square in part 15 1, the colors in part 2 being irregularly arranged.

In testimony whereof, I have affixed my signature in the presence of two witnesses.

MATHEW M. HYLAND.

Witnesses:
